(57) **CLAIM**

The ornamental design for an air purifier in a furniture article, as shown and described.

DESCRIPTION

FIG. 1 is a bottom, front-side perspective view of an air purifier in a furniture article according to a first embodiment. FIG. 2 is a top, front-side perspective view of the air purifier in a furniture article of FIG. 1.

FIG. 3 is a bottom, front-side perspective view of an air purifier in a furniture article according to a second embodiment; and,

FIG. 4 is a top, front-side perspective view of the air purifier in a furniture article shown in FIG. 3.

The legs of the article in FIGS. 3 and 4 are shown with a symbolic break in their length. The appearance of any portion of the article between the break lines forms no part of the claimed design.

The broken lines represent structure or features that form no part of the claimed design.

1 Claim, 4 Drawing Sheets(56)
